CHECKERWORK FOR FURNACES

James E. MacDonald, Latrobe, Pa.

Application November 20, 1944, Serial No. 564,261

3 Claims. (Cl. 263—51)

1

My invention relates to checker brick structures here shown as employed in a blast furnace stove, but which can also be employed in connection with other types of furnaces.

One object of my invention is to provide a checker structure wherein the bricks are of such shape that they can conveniently and accurately be laid to form checker flues and which provide lateral relief or flow passages between the various vertical flues, without materially detracting from the strength of the checkerwork as a whole, and wherein there will not only be equalization of flow pressures in the various flues but if clogging occurs in any flue, only a small portion of the flue will be rendered ineffective, because of the lateral relief passages between flues.

Another advantage incident to my invention is the provision of more extended heating surface area for a given size of bricks, as compared to bricks of conventional forms.

Another object of my invention is to provide a structure of the character referred to, wherein lateral relief passageways have the upper and lower portions of their walls so sloped as to reduce resistance to the gas flow and current eddies, and wherein there is little danger of the passageways becoming clogged.

A further object of my invention is to provide a checkerwork structure of such form that bricks extending in one horizontal direction can conveniently be vertically stepped or offset with respect to adjacent bricks that extend laterally or crosswise of said direction, without detracting from the symmetry of the checkerwork as a whole.

Some of the forms which my invention may take are shown in the accompanying drawing wherein Figure 1 is a fragmentary vertical view, partly in section, of a blast furnace stove embodying my invention; Fig. 2 is a sectional plan view on an enlarged scale, through a portion of the checkerwork of Fig. 1; Fig. 3 is a perspective view of one of the bricks of Fig. 2; Fig. 4 is an enlarged elevational view of a portion of the structure of Fig. 1; Fig. 5 is a perspective view showing a modification of the bricks of Figs. 1 to 3, and Fig. 6 shows still another modification.

Referring first to Figs. 1 to 4, it will be understood that the stove will be operated in a manner common in this art, namely the heated and cold air or gas will be circulated through the stove alternately, in opposite directions, for desired periods of time. The checkerwork 1 is supported on arches 8 and rider bars 9 which may be

2

of any suitable well known form. Each brick 10 is formed substantially as shown in Fig. 3 and each is provided with vertical ribs 11 and horizontally-extending depressions or recesses 12 in its vertical edges. The bricks are preferably all of the same size, except for certain bricks in the top and bottom courses, as will be hereinafter explained. One series of bricks 13 extend horizontally in one direction and the other series of bricks 14 extend crosswise relative to said direction. The bricks 13 are arranged in superposed relation with respect to one another, the ribs 11 of each brick have endwise engagement with the ribs of vertically-adjacent bricks so that the ribs 11 not only serve to assist in supporting the columns of bricks 13 but also provide extended heat-absorbing and heat-radiating area. The ends of the bricks 13 abut against the side faces of adjacent bricks 14 as shown more clearly in Fig. 1, the depressions 12 forming passageways between the ends of the bricks 13 and the sides of bricks 14, the ribs 11 compensate for the loss in strength that is occasioned by recesses 12. All superposed bricks have engagement with one another on their horizontal surfaces throughout their entire length, which makes for greater stability of the structure than if their upper and lower corners were cut away to form the lateral passages. The bricks 14 are similarly arranged with respect to one another and to the bricks 13, so that vertical flues 15 are formed and there are lateral passageways through each series (at 12), and at most points throughout the checkerwork, each flue 15 has a lateral communication with four adjacent flues.

It will be seen that if abnormally high pressure flow tends to occur in any flue, there will be relief thereof in lateral directions to other flues, thus equalizing flow pressures in the various flues and producing better uniformity of heat absorption and radiation throughout the checkerwork. Again, if one flue becomes clogged, the gas or air entering at either end of the flue will be by-passed around the obstruction, through the passageways at 12, thus permitting the major portion of the flue to function in substantially its normal manner.

In order to avoid horizontal shifting of one course of bricks on another, as through thermal expansion or contraction or slight distortion of the furnace structure, I provide a vertically-stepped relation as between the courses in which the bricks 13 are laid and the courses of bricks 14. To this end, the lowermost courses of bricks

14 (as shown in Figs. 1 and 4) are of one or two inches less height than the remaining bricks 14 in each column, so that each succeeding brick 14 will partly overlap (on vertical lines) all the other bricks 13 with which it has laterally-abutting engagement. At the top of the checkerwork, the bricks 13, forming the top course, are similarly vertically shortened in order that their top surfaces will be in the same horizontal plane as the top surfaces of the bricks 14.

In Fig. 5, I show a brick 16 that can be utilized in the same manner as the bricks 13 and 14, to form the checkerwork. In this case however, recesses 17 in the vertical edges of the bricks are inclined so that the streams of gas and air can flow therethrough more smoothly and with a reduction of eddy currents tending to result from the impingement of the gas stream on the upper and lower walls of these passageways, in either direction of flow. Also, the sloping surfaces reduce the danger of dust collecting in and clogging these passageways. The dust not only tends to slide off the lower surfaces of the passageways, but down-flowing gases will tend to blow the dust off more readily than if these surfaces were horizontal.

Fig. 6 shows another modified form of brick that can be used instead of the bricks of Figs. 1 to 5. In this case, each brick 18 has median ribs that are cut away or recessed at 20, to provide the lateral passageways. The smooth, straight vertical ends of each brick abut against the ribs 19, when the bricks are assembled as are the bricks in Figs. 1 to 3.

I claim as my invention:

1. Checkerwork for furnaces, comprising vertical flues formed of bricks in superposed relation and each having vertical ribs in abutting relation with ribs of vertically-adjacent bricks, and certain bricks having their vertical edges in abutting engagement with vertical sides of horizontally-adjacent bricks, the said edges having horizontally-extending depressions formed therein, to provide lateral passageways between the flues, the depressions each being symmetrically dis-

posed with respect to the horizontal median plane of its brick, and each being of materially less vertical width than the edge of its brick and having its upper and lower walls so inclined as to have the passageways slope from each flue to another flue.

2. Checkerwork for furnaces, comprising vertical flues formed of bricks in superposed relation and each having vertical ribs in abutting relation with ribs of vertically-adjacent bricks, and certain bricks having their vertical edges in abutting engagement with vertical sides of horizontally-adjacent bricks, the said edges having horizontally-extending depressions formed therein, to provide lateral passageways between the flues, the upper and lower walls of the depressions being so inclined as to have the passageways slope from each flue to other flues.

3. Checkerwork for furnaces, comprising vertical flues formed of bricks in superposed relation, with certain bricks having their vertical edges in abutting engagement with vertical sides of adjacent bricks, there being lateral passageways formed through the bricks of the checkerwork and the upper and lower walls of the passageways being so inclined as to have the passageways slope from each flue to other flues.

JAMES E. MACDONALD.
